UNITED STATES PATENT OFFICE.

LEWIS B. KENNEDY, OF ST. LOUIS, MISSOURI, ASSIGNOR TO THE KENNEDY DRY PRESS BRICK MACHINE MANUFACTURING COMPANY, OF PUEBLO, COLORADO.

BRICK-MACHINE.

SPECIFICATION forming part of Letters Patent No. 414,055, dated October 29, 1889.

Application filed September 5, 1889, Serial No. 323,024. (No model.)

To all whom it may concern:

Be it known that I, LEWIS B. KENNEDY, a citizen of the United States, residing at St. Louis, in the State of Missouri, have invented 5 new and useful Improvements in Brick-Machines; and I do hereby declare the following to be a full, clear, and exact description of said invention, reference being had to the accompanying drawings, and to the letters of 10 reference marked thereon, which form a part of this specification.

My invention relates to improvements in brick-machines, and is designed as an improvement on the machine for which Letters 15 Patent of the United States were granted to me September 8, 1885, No. 325,940.

The object of my invention is to dispense with the heavy bed-plate to which the toggle-levers are attached, and also the rods which 20 connect the bell-crank levers, and connect the bell-crank levers which operate the plungers direct with the toggle-levers, said toggle-levers being operated by a pitman in substantially the same manner as in the patent above 25 named.

Referring to the drawings, Figure 1 is a longitudinal sectional view of my machine, showing the position of the working parts when the plungers are exerting their greatest 30 pressure on the clay in the mold. Fig. 2 is a similar view showing the levers in a depressed or lower position and the plungers from pressing contact with the clay.

A indicates the side frame of the machine, 35 which may be of any suitable or desirable construction and of any suitable material, braced or joined together in a suitable manner, and in the front end of which is mounted the mold-boxes and frame B for supporting 40 the same.

C indicates the upper and D the lower bell-crank levers. The bell-crank lever C is pivoted in the upper part of the frame A at a, while the lower lever D is pivoted in the lower 45 part of the frame at b. These angle or bell-crank levers C and D are for operating the upper and lower plungers E and F, and are connected to the plungers or cross-heads G and H, which support the plungers by means 50 of links I. The cross-heads G and H are

adapted to work in guides formed on the inside of the frame A, so that they will move in a true vertical direction and always register with the mold-boxes. The outer ends of the bell-crank levers C and D are connected to 55 the toggle-levers K direct, one or more of said toggle-levers being used, as occasion may require. The knuckles or jointed portions of the toggle-levers K are connected to the shaft L by means of the slotted pitman M, said pitman being provided with an extended portion N, on which is secured the friction-wheel O.

R is a double cam-plate mounted on the shaft L, and adapted to operate on the pitman M in the following manner: One side 60 of the plate R has a cam-surface S, which is flanged and diverges or radiates from a point on the shaft on which said cam-plate is mounted to a joint f, where it terminates. The other side of the cam-plate R is provided with a cam-surface T, which commences at or near the joint f, where cam S terminates, and converges toward the shaft L, terminating at the joint g near said shaft.

As the shaft L revolves in the direction of 75 the arrow, the cam S impinges against the front edge of the friction-wheel O and draws the pitman M backward, the slot V allowing the shaft L to pass therethrough and permitting said pitman to be drawn back. 80 This motion straightens the toggles, as shown in Fig. 1, and raises the outer ends at the bell-crank or angle levers, bringing the plungers E and F toward each other and exerting the proper pressure. Pressure having been exerted to form the brick, the continued rotary motion of the shaft L brings the end of the pitman M, or, rather, the rear face of the friction-wheel, against the flanged portion h of the cam T, which, owing to its convergency 85 90 toward the axis of shaft L, pushes the pitman M forward, bending the toggles, as shown in Fig. 2, thus moving the plunger E upward and the cross-head H of the lower plunger downward. The lower plunger in the meantime is forced up by the lever A², which is operated by the cam B² on the wheel C² to eject the newly-formed brick from the mold, as 95 shown in Fig. 2.

The devices for feeding the clay to the mold 100

and for pushing the newly-formed brick from off the top of the lower plunger are of the usual and well-known kind, and need not now be shown, as they are shown, described, and 5 claimed in my patent of September 8, 1885, No. 325,939.

Having thus described my invention, what I claim, and desire to secure by Letters Patent, is—

- 10 1. In a brick-machine of the character described, the compression-plungers attached to the bell-crank levers by means of links, said levers being connected at their outer ends by toggle-levers operated from a continuously-15 rotated shaft, as set forth.

2. In a brick-machine, the angle or bell-crank levers C and D, pivoted in the sides of the machine, said levers being connected to the plungers by means of links which yield in opposite directions, the outer ends of the 20 angle or bell-crank levers operated from a continuously-revolving shaft.

In testimony whereof I affix my signature in the presence of two subscribing witnesses.

LEWIS B. KENNEDY.
